AQUARIUM FILTER

Morris R. Gare, 4 Bruen St., Hillside, N.J. 07205

Filed Aug. 5, 1966, Ser. No. 3,348

Term of patent 14 years

(Cl. D91—1)

FIG. 2

FIG. 1 is a perspective view of an aquarium filter embodying my new design, the center thereof being broken away to indicate indeterminate length; and

FIG. 2 is a side elevational view thereof.

I claim:

The ornamental design for an aquarium filter, as shown.
